UNITED STATES PATENT OFFICE.

JOHN W. CURRAN, OF NEWPORT, KENTUCKY.

OIL-CIRCULATING JOURNAL-BOX.

1,248,820.

Specification of Letters Patent.

Patented Dec. 4, 1917.

Application filed June 19, 1916. Serial No. 104,569.

To all whom it may concern:

Be it known that I, JOHN W. CURRAN, a citizen of the United States, residing at Newport, in the county of Campbell and State of Kentucky, have invented a new and useful Oil-Circulating Journal-Box, of which the following is a specification.

The present invention relates to journal boxes, and has particular reference to an improved construction of that type of journal box which is used on freight and passenger equipment cars, the improvements being designed to strengthen the journal box, and to more efficiently lubricate the 15 journals mounted therein.

An object of this invention is to provide a journal box, which meets all of the requirements of the Master Car Builders' Association rules, and which at the same 20 time is provided with novel means for effecting a constant circulation of the oil, when the journal is in motion, and which will prevent the excessive waste of the oil which occurs by the use of all prior journal boxes.

This invention also aims at the provision 25 of means, in a journal box construction, which will hold the waste from rolling or shifting, and jamming against the side of the journal box, and prevent the waste from 30 wiping off the oil from the journal, which would create undue friction and cause undue heating of the journal and the parts bearing against the same.

A further object of the present invention 35 is to provide a passage or chamber in the bottom of the journal box, through which the oil may freely flow as it is returned from the journal, and which is not separated from the waste by a perforated wall, or the 40 like, but which is closed at one side by the waste only, the waste freely absorbing the oil, and there being no openings to become clogged, nor inaccessible pockets to catch grit and dirt.

A still further object of this invention is 45 to improve journal boxes to accomplish the above outlined results, without placing any loose or separate parts in the box. The invention is embodied in a construction which 50 is integral and cast with the journal box; which adds but little weight to the box, and which incurs but slight increased cost in the manufacture of the box.

The present invention also provides a 55 journal box, for passenger equipment cars, or where the journal box is mounted in a

pedestal, which is of such construction that the bearing surface between the journal box and the pedestal is increased substantially one hundred per cent. This feature of the 60 invention doubly increases the life of the journal box, and the life of the pedestal; prevents the wearing of shoulders on the pedestal and prevents the tilting of the journal box, such conditions resulting in the 65 jarring of the passenger equipment cars when in transit; and prevents the breaking down of the journal box, which latter is a factor of danger.

Other objects and advantages of this invention, which are of more or less importance than the above, will be fully brought out in the following specific disclosure of the present preferred embodiment, the same being illustrated in the accompanying drawings, wherein:

Figure 1 is a side elevation of a journal box for passenger equipment cars, showing the improved lateral bearing surface for contact with the pedestal.

Fig. 2 is a top plan view of the same.

Fig. 3 is a longitudinal central section through the journal box with a journal mounted therein, and showing the improved interior construction of the box.

Fig. 4 is a horizontal section through the same on the line 4-4 of Fig. 3.

Fig. 5 is a transverse section through the journal box on the line 5-5 of Fig. 3, showing the journal packing in position.

Fig. 6 is a sectional perspective view, taken through the box looking down into the bottom thereof, and showing the location of the bottom and transverse flanges and the inclined partition wall.

Referring to these drawings, wherein like parts are designated by similar numerals of reference throughout the several views, 10 designates an integral journal box casting of the usual approved construction and design, as shown in Figs. 1 and 2. As shown in Figs. 3, 4 and 5, this journal box 10 has, at its rear end, the usual transversely extending dust guard chamber 11; a suitable dust guard 12 in the chamber 11, and which is mounted in the usual manner on the dust guard bearing 13 of the axle 14, the latter having a journal 15 projecting into the rear end of the journal box 10, and provided on its extremity with the usual axle collar 16; 110 has the usual journal bearing 17 against which the journal 15 bears; has the usual

journal bearing key 18 to support the bearing 17; and has a cover 19 hinged in the usual manner upon the forward end of the journal box to close the same.

- 5 The present invention provides certain additions to the integral construction of the journal box 10, which strengthen the bearing surfaces of the box at its points of engagement with the usual supporting pedestals, which retain the oil in the box, and which effect the complete and continuous circulation of the oil when the journal 15 is in motion. As shown in Figs. 3 to 6 of the drawings, the journal box 10 is provided 10 in each side with a horizontal bottom flange or wall 20. The flange or wall 20 is integral with the adjacent wall or side of the box 10, and preferably tapers in thickness from the side of the box to its longitudinal free edge. 15 20 The flanges 20 are located but a short distance above the bottom 21 of the journal box, to provide a relatively small oil receiving channel or chamber along the side of the journal box beneath the flanges 20. 25 30 The flanges 20 project inwardly from the opposite sides of the journal box throughout a greater portion of the length of the same, being merged with the outer curved wall of the box, and have upper inwardly sloping faces. The said channels or chambers for the oil beneath the flanges are open along their inner adjacent opposite sides throughout the entire length of the box, so that the oil is permitted to flow freely from 35 beneath the flanges 20 over the bottom of the box.

The inner ends of the flanges 20 connect with an upwardly extending and rearwardly inclining inner partition wall 22. This partition wall 22 extends substantially half way up within the journal box 10, and is inclined sufficiently to provide a relatively large space between the lower end of the same and the dust guard 12. This partition wall 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540

The partition wall 22 has, at its lower end, a horizontal forwardly projecting flange 23, which extends transversely across the rear end of the journal box 10 in the plane of the flanges 20, and which merges into and connects with the inner ends of the same. This transverse flange 23, like the flanges 20, 55 tapers toward its free edge, and provides an inclined upper face adapted to direct oil, falling on the flange, into the central portion of the journal box.

A slot or passage 24 is formed through the 60 transverse flange 23, and through the lower end of the partition wall 22, to permit the free flow of oil from behind the wall 22 forwardly into the journal box. The bottom 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540

a transversely extending oil well 25, formed preferably by the depression of the bottom 21 at that point, to receive and collect oil which is thrown off from or dropped by the journal. The upper edge of the partition 70 wall 22 is spaced from the dust guard 12 to provide therebetween a passage sufficient only to permit the oil to pass down into the well 25 from the journal 15.

From Fig. 5, it will be noted that the 75 usual journal packing 26 is compressed or jammed into the lower part of the journal box 10, and is wedged or forced down between, and slightly beneath, the free edges of the flanges 20, to bind and hold the packing 26 in the bottom of the box. The packing 26 forms opposite lateral walls along the inner opposite sides of the lateral oil channels to confine the bulk of the oil beneath the flanges 20, and to permit the free absorption 85 of the oil by the packing or waste through the entire length of the box, without the passage of the oil through perforated walls, or the like, which frequently become clogged. The bottom flanges 20 are spaced 90 above the bottom 21 a sufficient distance only to permit the wedging of the packing 26 beneath the free edges of the flanges. It will be noted that the width of the flanges is greater than their distance from the floor 95 or bottom of the box and that the flanges are closer to the bottom of the box than they are to the journal. This arrangement of the flanges prevents the packing from extending too far beneath the same, and provides for an uninterrupted oil passage in each side of the journal box extending from end to end thereof.

The wedging of the packing between the flanges 20 insures the retention of the packing 105 in the central portion of the journal box, and prevents the packing from becoming jammed against the side of the box, in which position it bears with undue friction against the journal 15, and wipes off 110 all of the oil from the same. With the journal boxes having no means for holding the packing in place, the journal bearings and the journals themselves become heated to an excessive degree.

The journal box 10 has the usual external 115 vertically extending ribs 27, arranged near the opposite ends, and at the opposite sides of the box 10, for reinforcing the latter.

A feature of this invention is to provide 120 bearing blocks 29, which may be cast integral with the box, and which are disposed on opposite sides of the box and midway between the end ribs 27, and are of substantially the same width and thickness as the 125 intermediate bearing ribs usually employed. These blocks 29 increase the bearing surfaces over one hundred per cent. at the opposite sides of the journal box, and preferably extend, as shown to advantage in Fig. 130

1, from the bottom of the box to a point substantially two-thirds the height of the journal box.

Vertical ribs 28 extend upwardly from the 5 upper end, and from the opposite edges of the bearing blocks 29, the ribs 28 being spaced apart, and the intervening upper edge of the blocks 29 being beveled outwardly, as at 30, to prevent accumulations of 10 dirt, moisture, and the like, which would tend to grind and injure the bearing faces.

When the journal box is mounted in a pedestal, of the approved and well known construction, the blocks 29, at the opposite 15 sides of the journal box, present broad flat bearing faces for contact with the transversely extending reinforcing webs of the pedestal, so that the usual grooving and weakening of these webs cannot take place, 20 as is the result with the use of the spaced apart vertical ribs now usually formed at the opposite sides of the journal box. The journal box usually has about one and one-half inches vertical play in the pedestal, 25 and the blocks 29 are made of sufficient height to provide ample bearing surfaces for the journal box against the pedestal at all positions of the journal box. As the webs of the pedestal, and the blocks 29 30 of the journal box, have relatively broad faces lying in contact throughout practically their entire extents, the lives of the pedestal and the journal box are considerably prolonged, on account of the wide distribution 35 of frictional contact or pressure which is had between the journal box and the pedestal.

In operation, when the journal 15 is rotated, its frictional contact with the bearing 40 17 heats the journal, and the heat of the journal increases the capillary action of the oil in the waste. The oil is thus fed upwardly against the journal from the bottom of the journal box.

45 The more friction between the journal 15 and its bearing 17, the more heat is produced, and consequently the more rapid is the absorption of the oil by the waste, as the latter feeds the oil upwardly against the journal. The oil which tends to pass out of the rear end of the journal box is thrown off from the inner end of the journal against, and into the passage behind the wall 22, and is deposited in the oil well 25. Oil flows 50 55 forwardly from the well 25 into the lateral channels beneath flanges 20, and from there it is absorbed by the packing 26 and carried upwardly against the face of the journal 15.

60 The oil which drips upon the upper face of the inclined partition wall 22 is deflected downwardly over the wall, through the slot 24, or over the flange 23 into the bottom of the journal box.

65 It will thus be observed that there is a

free circulation of oil, and that there are no perforated walls, screens, or the like, to impede the flowing of the oil. The well 25 is depressed in the bottom 21 of the journal box to not only retain a quantity of oil in 70 the well, but also to catch sediment and any foreign substance which may be found in the oil.

These flanges 20, and the partition wall 22, provide ample space for a quantity of 75 oil, and prevent the forcing out of the oil from the box when the waste, or journal packing, is squeezed into the box in the usual manner. When the waste is forced into the journal box, the oil is forced to the 80 top, and instead of flowing out of the inner or back end of the box onto the ground, runs into the space between the partition 22 and the dust guard 12, and circulates through 85 the lateral channels, and is absorbed by the waste.

The oil chamber, between the partition 22 and the dust guard 12, will also contain air, which will assist in maintaining the oil, and surrounding parts of the journal box, from 90 overheating. The partition wall 22 confines the packing in the journal box, and holds it out of the oil chamber.

The increased bearing surfaces at the opposite sides of the journal box 10 materially 95 increase the life of the box, and the life of the pedestal in which the box may be mounted, and effect the smooth riding of the passenger equipment cars.

What is claimed is:—

1. A journal box having spaced integral longitudinal flanges arranged along each side and also transversely at the inner end of the box, said flanges being arranged in substantially the same horizontal plane and 105 located at points nearer to the bottom of the box than to the journal thereof and having their upper faces inclined, the two side flanges joining with the end flange and all three flanges being spaced from the bottom 110 of the box, so as to provide oil channels between said flanges and the bottom of the box, whereby packing may be wedged in the space between the edges of the flanges, and an oil chamber at the inner end of the box 115 communicating with the channels beneath said flanges and adapted to receive oil dropped from the journal.

2. A journal box having spaced integral longitudinal flanges arranged along each 120 side of the box, and a transverse flange provided at the end of the box, the longitudinal flanges joining with the transverse flange at the inner end of the box, so as to provide a substantially continuous flange, which 125 flange is located entirely below the plane of the bottom of the journal, said flanges being spaced above the bottom of the box, so as to provide oil channels beneath the same, and also being tapered toward their outer ends 130

- and defining a rectangular space of materially smaller dimensions than the box, in which space packing may be received below the journal and wedged in place, said packing thereby constituting the top wall of said channels.
3. A journal box having inwardly projecting substantially horizontal flanges provided at the sides and end of the box and spaced above the bottom of the latter, said flanges having a width greater than their distance from said bottom, whereby when packing is wedged between the flanges inclosed channels will be formed with the packing serving as the top wall thereof.
4. A journal box having an integral partition wall arranged transversely in and spaced at the top and bottom from the inner end of the box, and also spaced at its lower end from the bottom of the box, said partition wall fitting at its upper edge around the journal, and integral flanges arranged longitudinally along the opposite sides of the box and also transversely along the lower end of the partition wall, the transverse flange merging with the said partition wall and all of said flanges extending inwardly from the sides and end within the box at points considerably below the bottom of the journal and spaced from the bottom of the box, whereby packing may be wedged between the edges of said flanges, said flanges and said partition wall defining a communicating oil space or chamber along the bottom and at the inner end of the box, to permit oil dropped from the journal to be delivered back of the partition wall and circulate beneath said flanges to the packing held by the flanges.
5. A journal box having an integral partition wall arranged transversely in and spaced from the inner end of the box from the top to the bottom, and also spaced at its lower end from the bottom of the box, said partition wall being curved at its upper edge to fit around the journal, and inclined downwardly away from the inner end of the box so that its lower end is spaced farther away from the inner end of the box than its upper end, and integral bottom flanges arranged longitudinally along the opposite sides of the box and also transversely along the lower end of the partition wall, the transverse bottom flange forming a continuation of the said partition wall and merging therewith and also merging into the longitudinal bottom flanges, all of said bottom flanges being spaced from the bottom of the box and being located nearer to said bottom than to the journal and having their upper faces inclined and their lower faces substantially horizontal, whereby packing may be wedged in the space between said flanges, the said flanges and said partition wall defining a communicating oil space or chamber

along the bottom and at the inner end of the box, to permit oil dropped from the journal to be delivered back of the partition wall and circulate beneath said flanges to the packing held by the flanges.

6. A journal box having a partition wall arranged transversely in and spaced from the inner end of the box and forming therewith a chamber adapted to receive oil from the journal and the forward portion of the box, and bottom flanges arranged along the opposite sides of the box in spaced relation to the bottom thereof and with their opposed inner edges in spaced relation to each other, said flanges being adapted to form with packing held therebetween suitable channels, said partition wall having an opening at its lower end, whereby the circulation of oil from the chamber to the packing and back to the chamber is permitted.

7. A journal box having a dust guard at the inner end thereof, an integral partition wall arranged transversely in and spaced from the inner end of the box and from the dust guard forming a chamber for receiving oil and also spaced at its lower end from the bottom of the box, an oil well in the bottom of the box directly below the partition wall, said partition wall being curved at its upper edge to fit around the journal and inclined inwardly and downwardly, and bottom flanges arranged along the opposite sides of the box and also along the lower end of the partition wall and extending inwardly within the box so as to contract the space thereof, said flanges being spaced from the bottom of the box so that packing may be wedged therebetween and form inclosed channels therewith, whereby oil dropped from the journal is delivered back from the partition wall and circulated through the channels back to the packing.

8. A journal box having a dust guard in the inner end thereof, a partition wall extending transversely across the inner end of the journal box adjacent to the dust guard, and inclining downwardly away from the dust guard to provide an oil chamber between the dust guard and the partition wall, a horizontal flange provided at the lower end of the partition wall, and longitudinally extending flanges projecting inwardly toward each other, and arranged along the opposite sides of the journal box, said flanges being disposed in spaced relation to the relation to the bottom of the journal box to provide oil channels in the sides of the box, and said partition wall terminating above the bottom of the box to admit oil from the oil chamber into said channels.

9. A journal box, a transverse partition wall arranged at the inner end of the box, said partition wall having its upper end spaced from the inner end of the box to permit the passage of oil downwardly

- therebetween, and having its lower end spaced from said inner end of the box and above the bottom thereof to provide a chamber for oil, and flanges projecting inwardly 5 from the side walls of the box and from the partition wall in spaced relation to the bottom of the box, to permit the free circulation of the oil from beneath the partition wall, said partition wall and the flange projecting from the same having a slot therein to permit oil flowing downwardly over the wall to pass into the oil chamber.
10. A journal box having exterior vertically extending bearing blocks arranged upon the opposite sides and intermediate the ends of the journal box to provide substantial bearing faces at the opposite sides of the journal box for contact with a pedestal.
- 15 20. 11. A journal box having exterior vertically extending bearing blocks arranged upon the opposite sides and intermediate the ends of the box, said blocks extending from the bottom of the journal box 25 to a point near the top of the box to provide a substantial bearing surface at each
- side of the box for contact with a pedestal, the journal box also having spaced apart vertical ribs extending upwardly from the upper ends of the bearing blocks and from 30 the opposite edges of the same, the upper ends of the blocks between the ribs being beveled outwardly.
12. A journal box having on each side an exterior vertically extending bearing block 35 being of a width and height to substantially correspond to the width and height of the reinforcing web in the side of the usual pedestal in which the journal box is adapted to be mounted, said bearing blocks providing broad bearing faces to distribute the pressure and frictional contact between the journal box and the pedestal and prevent undue wearing of the same at any one point.

In testimony, that I claim the foregoing 45 as my own, I have hereto affixed my signature in the presence of two witnesses.

JOHN W. CURRAN.
